DESIGN FOR A COMBINED CORNICE, CUR- TAIN AND DRAPERY BRACKET

William Lyons, Lynbrook, N. Y., assignor to
William Lyons Novelty Co., Inc., New York,
N. Y., a corporation of New York

Application April 4, 1944, Serial No. 113,136

Term of patent 14 years

(Cl. D21—1)

To all whom it may concern:

Be it known, that I, William Lyons, a citizen
of the United States, resident of Lynbrook, in
the county of Nassau, State of New York, have
invented a new, original, and ornamental Design
for a Combined Cornice, Curtain and Drapery
Bracket, of which the following is a specifica-
tion, reference being had to accompanying draw-
ing, forming part thereof,

In the drawing, the figure is a perspective
view of a combined cornice, curtain and drapery
bracket, showing by new design.

I claim:

The ornamental design for a combined cor-
nice, curtain and drapery bracket, substantially
as shown.

WILLIAM LYONS.
